Primary Examiner—Susan J. Lucas*Assistant Examiner*—Cynthia E Ramirez*Attorney, Agent, or Firm*—Pandiscio & Pandiscio[57] **CLAIM**

The ornamental design for a wheeled container, as shown and described.

DESCRIPTION

FIG. 1 is a perspective view of a wheeled container incorporating the invention;

FIG. 2 is a front view in elevation of the same wheeled container;

FIG. 3 is a rear view in elevation of the same wheeled container;

FIG. 4 is a right side elevation of the wheeled container;

FIG. 5 is a top plan view of the same wheeled container; and,

FIG. 6 is a bottom plan view of the same wheeled container.

The view of the wheeled container from the left-hand side is

a mirror image of FIG. 4.
